UNITED STATES PATENT OFFICE

JOHN G. ANDREWS, OF HAMILTON, OHIO, ASSIGNEE, BY MESNE ASSIGNMENTS, TO
PANELON UNDERWEAR COMPANY, OF HAMILTON, OHIO, A CORPORATION OF OHIO

UNDERGARMENT AND METHOD OF MAKING SAME

Application filed September 24, 1926. Serial No. 137,581.

My invention relates to undergarments such as bloomers, pajamas, combination slippers, and all garments covering the lower limbs, for ladies', men's and children's wear, and to methods of making such garments, including the cutting of the garments with little waste from suitable material.

It is the object of my invention to provide a method by which garments may be readily cut, particularly from tubular material. It is a further object to provide sets of patterns for cutting out the material for such garments, which patterns may have identical portions, the variations for different sizes being made by slight modifications in shape of several of the component parts without the necessity of changing other of the component parts.

It is my object to provide garments in which form fitting garments for women's figures will be provided, which will stretch along lines in the goods which will readily give, so that there will be no tendency to bind at the crotch. It is a further object to provide garments in which the tendency to sag at the crotch will be also avoided during normal erect position of the wearer's body.

Referring to the drawings in which I have illustrated preferred patterns and garments which can be made in accordance with my invention:—

Figure 1 is a diagram showing how ladies' bloomers may be cut out from a tubular piece of material.

Figure 2 is a front elevation of a finished garment made from a pattern such as is shown in Figure 1.

Figure 3 is a rear elevation of the finished garment shown in Figure 2.

Figure 4 is a diagram showing a preferred type of pattern for the lower part of a pajama garment.

Figure 5 is a diagram showing a preferred type of pattern for a lady's combination slip-on garment.

Figure 6 is a front elevation of the finished garment made from the pattern shown in Figure 4.

Figure 7 is a front elevation of the finished

slip-on made from the pattern shown in Figure 5.

Referring first to Figures 1-3, the garments are preferably made from tubular pieces of material as indicated at 1. The outside leg covering pieces are formed by the rectangular portions 2, which for a given length of garment regardless of size, are of similar varied shape and dimensions. A central panel piece 3 is formed by cutting the tubular edges of the material along the lines indicated. The panel piece will, when spread out, be twice the size of the piece shown in the drawings. Pieces 4 are next cut out, and they are stitched to the edges of the rectangular pieces and the band as indicated in Figures 2 and 3. The bloomers, after having been cut out along the heavy lines indicated in Figure 1, are then stitched together as indicated by dotted lines, and the novel garment is finished with elastic at the waist band and at the bottom of the legs as shown at 5. In wearing the bloomers, it is possible for a wearer to stretch the legs at any angle without the garments tending to bind at the crotch. The principal reason for this is that there is no line of stitching or inside seam down the inside leg line, and the pieces 4 are stretched in the direction of the length of the pieces. If there were stitches down the inside seam, the threads would prevent the material from stretching. At the same time, while I provide a garment which will stretch readily with the distension of the legs of the wearer, I provide a garment which, when the legs are together in normal position, will not have any tendency to sag down and make wrinkled folds of material between the legs. Figure 1, it will be observed, provides the parts for two complete garments, there being four pieces 2, four pieces 4, and two pieces 3.

Figures 4-7 show respectively, patterns and finished garments made on the same principle as those indicated in Figures 1-3. There are thus the rectangular side pieces 2, the central panels 3, extending from the upper end of the garment in front to the upper end in back, forming garments with seamless crotch portions between the legs. The prin-

5 ciple of great economy in cutting material is present in all types of garments made in accordance with my invention, as the rectangular pieces which form considerably more than half the material used, can be cut with no waste at all.

10 My garments, further, are so stitched together, that the goods will stretch in the direction of their width most readily, which makes them easy to put on and arrange. The matter of so constructing the garments that the elastic bands will always be disposed at right angles to the longitudinal grain of the material is also an advantage.

15 Another feature which adds considerably to the wearing qualities of my garments are—reinforcing pads 6, which I stitch as shown in the crotch portions. It is within the scope of my invention to provide garments in which the portions 2 shall be of lace like material, and the other parts 3 and 20 4 of more woven or knitted material.

25 Having thus described my invention what I claim as new and desire to secure by Letters Patent is:—

30 1. In a lady's undergarment, rectangular pieces secured in the portion of the garment which cover the outer sides of the legs, a central panel securing the top inner edges of said rectangular pieces together in the front and back, said panel being wider at the top in front and back than in the intermediate portions, and pieces stitched to the central panel in the crotch portion, said pieces 35 also uniting the lower inner edges of said rectangular pieces together.

40 2. In a lady's undergarment, rectangular pieces secured in the portion of the garment which covers the outer sides of the legs, a central panel securing the top inner edges of said rectangular pieces together in the front and back said panel being wider at the top in front and back than in the intermediate portions, pieces stitched to the central panel in 45 the crotch portion, said pieces also uniting the lower inner edges of said rectangular pieces together, and said last named pieces forming seamless portions down the inner sides of the legs, said garment being freely 50 stretchable along the inner leg portions.

JOHN G. ANDREWS.
